(57) **CLAIM**

The ornamental design for a diverter valve, as shown and described.

DESCRIPTION

FIG. 1 is a perspective view of a diverter valve showing my new design;

FIG. 2 is a front elevational view thereof;

FIG. 3 is a left side view thereof, the opposite side being a mirror image of the side shown;

FIG. 4 is a top plan view thereof;

FIG. 5 is a bottom view thereof; and,

FIG. 6 is a rear view thereof.

The broken line showing a plumbing hole on the rear of the valve in FIG. 6 is included for the purpose of illustrating a portion of the diverter valve that forms no part of the claimed design.
